UNITED STATES PATENT OFFICE

98,916

DESIGN FOR A REFLECTOR FOR ELECTRIC LAMPS

Edward T. Camenisch, Chicago, Ill., assignor to
The Mantle Lamp Company of America, Chi-
cago, Ill., a corporation of Illinois

Application January 6, 1936, Serial No. 60,434

Term of patent 7 years

To all whom it may concern:

Be it known that I, Edward T. Camenisch, a citizen of the United States of America, residing at Chicago, in the county of Cook and State of Illinois, have invented a new, original, and ornamental Design for Reflectors for Electric Lamps, of which the following is a specification, reference being had to the accompanying drawing, forming a part thereof.

The figure is a perspective view of a reflector for electric lamps, showing my new design.

I claim:

The ornamental design for a reflector for electric lamps, substantially as shown.

In testimony whereof I affix my signature.

EDWARD T. CAMENISCH.
